INVENTOR

Albert P. Massey.

UNITED STATES PATENT OFFICE.

ALBERT P. MASSEY, OF WATERTOWN, NEW YORK.

QUICK-ACTION TRIPLE VALVE.

SPECIFICATION forming part of Letters Patent No. 511,206, dated December 19, 1893.

Application filed July 28, 1893. Serial No. 481,745. (No model.)

To all whom it may concern:

Be it known that I, ALBERT P. MASSEY, a citizen of the United States, and a resident of Watertown, Jefferson county, State of New York, have invented a new and useful Improvement in Quick-Action Triple Valves, of which the following is a specification.

My invention relates to quick action automatic brakes, wherein a sudden reduction of pressure in the train pipe causes a valve to open and admit fluid from the train pipe to the brake cylinder.

My purpose is to obtain a very quick opening of said valve when the proper reduction of fluid pressure in the train pipe is made.

The drawing is a section of one form of triple valve as used in the automatic brake system, with the quick action parts modified by my improvements.

In the drawing, 1 is a valve controlling a passage 2 which connects the train pipe chamber 3 and the brake cylinder chamber 4—4. A check valve 5 is also situated in the same passage to prevent a return flow of fluid from the brake cylinder chamber to the train pipe chamber.

6 is a piston in a cylinder. The under side of piston 6 is exposed to train pipe pressure through passage 7. The upper side of the piston 6 is exposed to reservoir pressure through passage 8, and the annular space next piston 12 through which air passes from the train pipe to the auxiliary reservoir.

9 is a light spring to close valve 1 and hold it on its seat when there is no fluid pressure in the train pipe chamber. 10 is an arm projecting from one side of valve 1. A shelf 11 is provided in the casing to form a fulcrum for arm 10 when the outside end is depressed.

The piston 12, graduating valve 13 and release valve 14 constitute the ordinary triple valve. The air passes from the train pipe through a charging groove in the cylinder above piston 12 to the auxiliary reservoir until both have the same pressure. Upon a reduction of pressure in the train pipe the preponderance of pressure in the reservoir moves the piston 12 to the left carrying with it valves 13 and 14. Valve 14 closes the exhaust and valve 13 admits air from the reservoir to the brake cylinder. Pistons 6 and 12 are each exposed on one side to train pipe pressure and

on the other to auxiliary reservoir pressure. A reduction of train pipe pressure below that of the auxiliary reservoir produces a stress 55 on each to move it away from the reservoir. The motion of piston 12 is resisted by the friction of the slide valves 13 and 14. The motion of piston 6 is resisted partly by the spring 9, but principally by the fluid pressure on the 60 back of valve 1, as the face of valve 1 toward the brake cylinder chamber is open to the atmosphere when the brakes are off. The area of this valve 1 is made sufficient to offer about twice as much resistance to movement of piston 65 ton 6 as the slide valves 13 and 14 offer to piston 12. This enables the engineer to operate the service portion of the apparatus by making only moderate reductions of pressure in the train pipe, sufficient to actuate piston 12 and 70 its valves without actuating piston 6 to open valve 1. The stem of piston 6 bears upon the arm 10 of valve 1 at some distance from the center of the valve. Any downward motion of the piston therefore tends to push the valve 75 open on the edge nearest the arm 10 and the other edge 15 becomes a fulcrum about which the valve turns until the outside end of arm 10 comes in contact with the shelf 11. When the arm comes in contact with the shelf 11 80 this becomes the fulcrum about which the valve turns until the piston has completed its full stroke and the valve is wide open.

The operation of the apparatus is as follows: When the train pipe, triple valve and 85 auxiliary reservoir are charged with fluid, the valve 1 is held to its seat partly by the spring 9, but principally by the fluid pressure in the train pipe chamber 3. The piston 6 has the same fluid pressure on both sides for the 90 lower side is open to train pipe pressure through 7 and the upper side is open to the same pressure through 8 and the annular space next piston 12, which is open to the train pipe through the charging groove. A 95 reduction of the train pipe pressure leaves a preponderance of pressure on the upper side of piston 6 which presses on the arm 10 of valve 1. When this preponderance of pressure reaches the predetermined resistance 100 offered by the spring 9 and the unbalanced fluid pressure upward on valve 1, the valve begins to open by being turned on the edge 15 which forms a fulcrum. This partial opening

of the valve allows fluid to flow from chamber 3 through passage 2 to brake cylinder 4 and instantly reduces the pressure in chamber 3 and thus gives greater preponderance of force to piston 6. As the fluid flows on the upper side of valve 1 it neutralizes or balances the fluid pressure below valve 1 and leaves only the resistance of the spring 9 to be overcome in further opening of the valve. 10 This discharge of fluid from chamber 3 and the removal of the greater part of the resistance from valve 1 enables the reservoir pressure to move piston 6 and throw valve 1 wide open instantly. During the latter part of the movement of valve 1 the outer end of arm 10 touches shelf 11, the fulcrum then changes from 15 to 11, and the whole valve is moved away from its seat. The object is thus accomplished of opening a very large opening 20 instantly between the train pipe and the brake cylinder when a predetermined difference of fluid pressure is attained between the train pipe and the auxiliary reservoir, while the apparatus remains very stable during minor 25 differences of pressure. When fluid pressure is restored to the train pipe the spring 9 raises the valve 1 to its seat and holds it there until the brakes are released. The removal of fluid pressure from the upper side 30 of valve 1 by the release of pressure from the brake cylinder restores the normal conditions first described. This arrangement of an emergency valve held on its seat by fluid pressure is shown in the application allowed 35 to me July 11, 1892, Serial No. 431,123, but the device now described is an improvement on that of the above mentioned application, because a much larger valve may be opened by a given difference in fluid pressures on 40 opposite sides of piston 6. The force of the piston is applied to valve 1 at first through a lever of the second order, with a fulcrum at 15 and a corresponding increase of power to open one side of the valve. When one side

is opened and the fluid pressure resistance 45 neutralized by the inflow of air on top of the valve, the lever arm reaches the other fulcrum 11 and the lever changes to one of the third order, thus giving a very quick motion to open the valve full. This same device 50 could be applied to the form of triple valve shown in the application above mentioned, Serial No. 431,123, as well as the one shown in the drawing.

What I claim as new, and desire to secure 55 by Letters Patent, is—

1. The combination with the train pipe, brake cylinder and quick action or emergency passage connecting the same, of a valve controlling said passage, and an operating piston 60 for said valve bearing upon one side or edge thereof.
2. The combination with a quick action or emergency valve of a free arm or extension thereof, an abutment beneath the end of the 65 arm, and an operating piston bearing upon the arm between the end thereof and the valve.
3. The combination with the triple valve having an emergency or quick action passage, 70 of an emergency valve controlling said passage, a spring sustained supporting plate carrying the valve at one end and having its other end free and lying above a fixed abutment in the triple valve casing, and a piston 75 exposed to reservoir pressure on one side and to train pipe pressure on the other, and having its stem resting upon the valve supporting plate between the end thereof and the valve. 80

In testimony that I claim the foregoing as my invention I have signed my name, in presence of two witnesses, this 25th day of July, 1893.

ALBERT P. MASSEY.
